UNITED STATES PATENT OFFICE.

EUGENE D. BOASSO, OF CHARENTON, LOUISIANA.

RAIL-JOINT.

SPECIFICATION forming part of Letters Patent No. 752,511, dated February 16, 1904.

Application filed November 30, 1903. Serial No. 183,232. (No model.)

To all whom it may concern:

Be it known that I, EUGENE D. BOASSO, a citizen of the United States, residing at Charenton, in the parish of St. Mary and State of Louisiana, have invented certain new and useful Improvements in Rail-Joints; and I do declare the following to be a full, clear, and exact description of the invention, such as will enable others skilled in the art to which it applies to make and use the same.

The invention relates to railroad and rail joints.

The object of the invention is to provide a joint of this character by means of which hammering incident to the passing of trains over the adjacent ends of rails will be avoided and life of the rail and wheel prolonged and the comfort of the passengers increased.

A further object of the invention is to provide a joint of this character which shall be simple of construction, comparatively inexpensive of production, and which will be prevented from creeping.

With these and other objects in view the invention consists of certain novel features of construction, combination, and arrangement of parts, as will be hereinafter more fully described, and particularly pointed out in the appended claims, reference being had to the accompanying drawings, in which—

Figure 1 is a perspective view of the adjacent ends of two railway-rails, showing them connected by my improved joint; and Fig. 2 is a cross-sectional view.

In the drawings, 1 denotes the adjacent ends of two railroad-rails seated upon a base-plate 2, having flanges 3, which project upward and snugly fit the edges of the base of the rail and project slightly above the same, as shown in

Fig. 2 of the drawings.

4 and 5 denote the splice-bars, angular in cross-section to fit the upper sides of the base of the rail and the sides of the web of the rail, and are provided with bolt-holes 6, through which and similar bolt-holes in the rail extend bolts 7 in the usual manner. The base portions of these splice-bars abut against the upwardly-projecting flanges of the base-plate and form a snug fit therewith. One of these splice-bars—5, for instance—is provided with

a head 8, adapted to lie against the side of the tread of the rails at their adjacent ends and project to a point not below the wearing-surfaces of the tread of the rails, so that the wheels of the train in passing over the adjacent ends of the rails will be supported at those points in the length of the track where the adjacent ends of the rails separate, owing to the contraction or otherwise. It will thus be seen that the jar incident to the wheels passing over these joints will be entirely overcome and the life of the rails and wheels be prolonged.

The head is constructed in a novel manner, as will be seen by referring to the drawings, in which the head is shown as being cast integrally with the vertical as well as with the laterally-extending portions of the splice-bar and as formed with a strong brace-rib 9. The lower and outwardly-projecting end of the head is adapted to seat in a recess 10, formed in one of the flanges of the base-plate, and is formed with a spike-notch 11, with which is adapted to be engaged one of the spikes used in fastening the joint to the ties. When thus fastened, the base-plate will be prevented from slipping or creeping with respect to the splice-bars, or vice versa.

From the foregoing description, taken in connection with the accompanying drawings, the construction, operation, and advantages of the invention will be readily understood without requiring a more extended explanation.

Various changes in the form, proportion, and the minor details of construction may be resorted to without departing from the principle or sacrificing any of the advantages of this invention.

Having thus described my invention, what I claim, and desire to secure by Letters Patent, is—

1. The combination with the adjacent ends of railroad-rails, of a plate supporting them and having flanges that project above their bases, one of said flanges having a notch in its upper side, and splice-bars bearing against the webs and on the bases of the rails and within the flanges of the said plate, one of said splice-bars having an upwardly-projecting

wheel-supporting head, spanning the space between the rails, and an outwardly-projecting extension engaging the notch in the flange of the plate.

- 5 2. The combination with the adjacent ends of railroad-rails, of a plate supporting the ends of said rails and provided with upwardly-extending flanges which engage the edges of the base of the rails and project a distance 10 above the same, one of said flanges having a notch or recess formed in its upper edge, splice-bars fitted to the webs and bases of said rails and confined between the flanges of said

plate, one of said splice-bars having a wheel-supporting head spanning the space between the ends of the rails and formed with an extension which projects into the notch or recess in the plate-flange, said extension having a spike-notch.

In testimony whereof I have hereunto set 20 my hand in presence of two subscribing witnesses.

EUGENE D. BOASSO.
